(57) **CLAIM**

The ornamental design for a folding tool including pliers, as shown and described.

DESCRIPTION

FIG. 1 is an isometric view from the upper right front of a folding tool including pliers, showing our new design;
FIG. 2 is a side elevational view thereof, an elevational view of the opposite side being identical therewith;
FIG. 3 is a top plan view thereof, a bottom plan view thereof being identical therewith;
FIG. 4 is a rear elevational view thereof; and,
FIG. 5 is a front elevational view thereof.
